United States Patent Office

Des. 223,997
Patented June 27, 1972

223,997

BOTTLE

Kenji Hanamura, Tokyo, Japan, assignor to
Tanco Co., Ltd., Osaka, Japan

Filed Dec. 31, 1970, Ser. No. 26,716

Term of patent 14 years

Int. Cl. D9—01

U.S. Cl. D9—157

FIG.1

FIG.2

FIG.3

FIG.4

FIG.5

FIG.6

FIG. 1 is a top plan view of a bottle showing my new design;

FIG. 2 is a side elevational view;

FIG. 3 is a bottom plan view;

FIG. 4 is a top plan view of another embodiment of my new design;

FIG. 5 is a side elevational view thereof; and

FIG. 6 is a bottom plan view thereof.

The bottle is symmetric, and the elevation view is the same from all directions.

I claim:

The ornamental design for a bottle, as shown and described.
